CHARLES W. CAHOON, OF PORTLAND, MAINE.

Letters Patent No. 83,457, dated October 27, 1868.

IMPROVEMENT IN STEAM-GENERATORS.

The Schedule referred to in these Letters Patent and making part of the same.

To all whom it may concern:

Be it known that I, CHARLES W. CAHOON, of Portland, in the county of Cumberland, and State of Maine, have invented certain new and useful Improvements in Propelling Carriages; and I hereby declare the following to be a full, clear, and exact description thereof, which will enable others to make and use my invention, reference being had to the accompanying drawings, forming part of this specification, in which—

Figure 1, plate 1, shows a side elevation of my invention.

Figure 2, plate 1, represents a sectional view of the pipe B and connections.

Figure 3, plate 1, represents a view of the screw-lever and joint.

Figure 4, plate 1, is a view of the pipe i and a section of the carriage.

Plate 2 exhibits a side sectional elevation of the carriage, and certain of my improvements therewith connected.

Figure 1, plate 3, shows an end view of a car, with the elevating-screw connected therewith, said screw having the revolving shaft.

Figure 2, plate 3, represents a side elevation of the same, having the rod for turning the car.

Similar letters and numerals refer to like parts in each of the plates and figures.

This invention consists in a novel means of supplying the carriage described in my patent of November 5, 1867, with hot water, for use in propelling the same, and also in a supplemental tank to the boiler where the water is heated, for the purpose of receiving the same after it has been used, as above, and before it is returned to the boiler for reheating, the object of which is, that it may be ejected from the carriage by its own pressure, and when that pressure becomes reduced below that in the boiler, as would necessarily be the case after it has performed its duty on the carriage.

It also consists in a pipe and valve for letting off water from the supply-pipe before it is uncoupled.

A represents a stationary boiler, having a pipe, B, leading up from the lower part of its water-space, and then horizontally, or nearly so, into the carriage, C. This pipe has a valve, a, for opening and closing it, a vertical pipe, b, with valve c in the same, and two ball-joints, D D, to impart flexibility to the pipe. It also has a holder, d, to prevent the pipe from turning when coupled, and also a coupling, E, which moves on or off the pipe, by means of the screw-thread on the same and on the pipe. This coupling is so made as to connect with the pipe i, leading out of the side of the carriage, which pipe also has a screw-thread upon it. By these means the coupling of the pipe B and pipe i is effected. The end of the coupling is made flaring, so that it may be readily adjusted to the carriage-pipe.

The object of the vertical pipe b is that, when the carriage has been charged with hot water, the pipe B

from the boiler may be uncoupled from the pipe i on the carriage without difficulty or danger, inasmuch as, when the valves c and a have been closed, the opening of the valve c drains the pipe B, and admits of the exit of the water therefrom naturally, and without being influenced by the pressure either from the water in the tanks or the boiler.

F represents an iron tank, placed on a frame near the upper part of the boiler, above the water-space, and having a pipe, f, leading into the boiler, and having a valve, g.

Another pipe, Z, with the valve y, leads upward into the open air.

Another pipe, G, leads first downward, then horizontally, from this tank, into the carriage. This pipe G has, like pipe B, double ball-joints, a holder, and coupling.

H represents double-reciprocating locomotive-engines, placed upon one end of the carriage, and connected with the wheels of the same by means of gearing, so that the operation of the engines will propel the carriage.

I represent two iron tanks, having each a pipe, h, leading from their top into the engines, being encased with tin, so as to leave an air-space between them and the same. From the bottom of the tin casing a small pipe, with a valve in the same, leads to the outside of the carriage, so as to conduct off any leakage which might take place from the tanks. These tanks are situated within the body of the carriage, and encased, about one foot from the outside of them, with wood, the space between being filled with dry sawdust, the same being for the purpose of retarding the conduction of heat.

Between the outside of the wooden casing and the sides of the carriages a space is left for a passage-way.

From the tanks I I extend lateral pipes i, passing through the casings of the tanks, and to just within the outside of the carriage, for connecting the same with the boiler, sliding doors being on the outside of the carriage, to enclose the same when disconnected. There are two of these pipes i to each tank, one at the bottom and another near the top, each having a valve in the same, and a screw-thread on the end, so that the tanks can be coupled to the boiler, and supplied therefrom. Glass water-gauges, j, are attached to each tank, so that it may be known when they are sufficiently charged with water.

k represents a valve in a pipe connecting the two tanks, so that their contents may be disconnected when desired. l l represent handles to valves in pipes h h, for regulating the flow of steam to the engines. They are placed at the side of the engines, and are pivoted to the bottom of the carriage, extending through the same, and having connecting-rods leading under the carriage, to the other end, being there attached to similar handles, so that the valves can be operated at either end of the carriage.

The general operation of my invention is as follows: Water being first heated in the boiler A, to as high a temperature as the construction of the same and the strength of the tank will safely admit of, the carriage is brought alongside of the boiler, so that the pipes *i* in the same will be nearly opposite the pipes B and G in the boiler. The end of the pipe B is then, by means of the two ball-joints D D in the same, brought in a line with the upper pipe, *i*, in the carriage, the coupling E being screwed outwardly until the pipe *i* enters the same. The valves *a* and *a'* are then opened, causing, by the pressure in the boiler, the tanks to be filled, the valves *z* *z'* being opened to let out the air and steam. When the tanks are charged with water, and it is desired to uncouple the carriage from the boiler, the valves *a* and *a'* are closed, the valve *s* is opened, and at the same time the valve *z* is closed, and after the pressure in the pipes is relieved, the coupling E is turned off from the end of the carriage-pipe, and the carriage is ready for duty.

When the heat of the water in the carriage becomes so much reduced as not to furnish the necessary power for propulsion, what is left therein may be returned again to the boiler, for reheating; and in order to accomplish this readily, the pressure should not be allowed to fall below eight or ten pounds to the square inch in the car-reservoirs, before recharging, in order that it may have force enough to eject itself therefrom up into the boiler-tank F. The connections for this purpose are made the same as for the purposes of supplying the carriage, and are attached to the pipe G, leading from the boiler-tank F, and the lower pipe, *i*, in the carriage-reservoirs, the valve *g* being shut, and the valve *y* being opened, the latter to let off the air and steam as the water enters the tank F. After the carriage has thus relieved itself, the lower pipe-valve, *e*, is closed, as well as the valve *y* in the boiler-tank pipe *z*. The valve *y'* is closed, and the boiler-tank pipe is then uncoupled.

The carriage-reservoirs may be then recharged, as before described. After this is done, the valve *y* in the boiler-tank should be shut, and the valve *g* in the pipe

f opened, in order that the contents of the tank F may flow into the boiler for reheating, closing the valve *g* when the tank F is emptied.

Having thus described my invention, I would recommend that in the construction of tanks for street-railroad locomotives, say for hauling one ordinary passenger-car, with its quota of passengers, it would be well to have them strong enough to endure a pressure of one hundred pounds to the square inch, and of a capacity to carry two hundred gallons of water, so that a sufficient stock of power may be had not to require very frequent recharging; and also that the engines be of sufficient diameter and capacity to give the necessary speed when the pressure is considerably reduced by exhaustion, inasmuch as the lower the pressure required, the less frequently will it be necessary to recharge the carriage. The opening of the induction-valve to the engine, when it is desired to keep up a uniform speed of the carriage, should, of course, be increased as the pressure decreases.

What I claim as my invention, and desire to secure by Letters Patent, is—

1. The boiler A, with the pipe B, flexible by means of the joints D D, having the coupling E, and valves, substantially as herein set forth and described.
2. The combination of boiler-tank F, with the boiler A, and with reference to the carriage C, substantially as herein described.
3. The combination of pipe G, flexible, as described, and having the coupling, whereby to convey the residuum of the carriage-reservoirs into the boiler-tank F, as described.
4. In combination with the boiler A, having a supply-pipe, B, for connecting with the carriage C, to supply the tanks therein, as described, the relief-pipe *b*, with its valve *c*, substantially as described.

CHAS. W. CAHOON.
